AIR-CONDITIONING METHOD AND APPARATUS

Jesse H. Davis, Baltimore, Md., and Samuel M. Anderson, Sharon, Mass., assignors to B. F. Sturtevant Company, Boston, Mass., a corporation of Massachusetts

Application July 18, 1931. Serial No. 551,614

20 Claims. (Cl. 62—117)

The present invention relates to air conditioning methods and apparatus and more especially to methods and apparatus particularly adapted for conditioning the air of passenger vehicles, 5 such as railway cars.

In the conditioning of air of passenger cars, the desired cooling effect is commonly secured by means of electrically driven refrigeration apparatus through the medium of water or other

10 liquid maintained at a relatively low temperature.

The necessary current for such apparatus is obtained from an axle driven generator without storage battery, the power requirements being so heavy as normally to prohibit the use of such 15 equipment. As a consequence, when the car slows down to a predetermined minimum speed, or stands in a station, the refrigerating apparatus becomes and remains inoperative.

It is the object of the present invention, to 20 provide a method and apparatus whereby during such low speeds or standing at stations, the cooling of the air will be continued so long as the water or other liquid is capable of producing any appreciable reduction of the temperature, 25 but upon the warming of the water, the transfer of heat from the water to the air will automatically be prevented so that heating of the air from the water will be impossible.

It is a further object to so construct and operate such apparatus that upon the car's again 30 exceeding such minimum speed, the water will automatically become capable once more of absorbing heat from the air to cool the same.

To the above ends, the invention consists of 35 a method and apparatus wherein the air is cooled by means of circulating water or other fluid in turn cooled by an intermittently driven refrigerating apparatus, the circulation of the cooling water being continued for a time after the 40 refrigerating apparatus has ceased to operate, automatically ceasing when the water becomes warm, and being resumed upon the refrigerating apparatus again becoming operative.

In the accompanying drawing is shown, somewhat diagrammatically, the preferred form of 45 the present invention.

The illustrated embodiment of the invention 50 comprises a fluid circulating air conditioning system including a spray device or a dehumidifier 2, of any usual or preferred form, through which air to be conditioned is continuously forced by a fan 4. The conditioned air leaving the dehumidifier is distributed through a duct 6, in any suitable manner, to different parts of the 55 vehicle. The operation of the dehumidifier, and

the flow of air therethrough, may be controlled by any suitable instruments sensitive to temperature and humidity conditions in the vehicle. Water, which constitutes the air conditioning medium, is continuously circulated through the 60 spray device by a pump 8. The outlet of the pump connects through a cooler 10 with the spray device and the outlet of the spray device leads to the inlet of the pump.

The water circulated through the spray device 65 is cooled in the cooler 10 by a refrigeration apparatus indicated diagrammatically by the compressor 11 driven by the motor 12 and the condenser 13. The refrigerant is circulated through the pipe lines 14 through the compressor, the condenser and the cooler. The refrigerator motor 12 is supplied with electric current by a generator 16 driven from the axle 18 of the vehicle through suitable gearing 19 and connected with the motor by leads 20.

The pump 8 for circulating the water is driven by an electric motor 22 which is energized by a battery 24. The battery may be continuously charged when the vehicle is in motion by an axle generator, not shown. The drive for the 80 pump 8 being independent of the refrigerator drive, the pump will continue to operate when the vehicle is stationary. Therefore, for a short stop, even though the refrigerator is inactive, the temperature of the circulating water may 85 be maintained sufficiently low for a considerable period and will be circulated to the spray nozzles to cool and dehumidify the air.

However, if the stop is an extended one, the 90 temperature of the circulating water increases so that eventually it becomes ineffective for proper conditioning of the air, and if continued to be sprayed into the air, will increase the temperature and humidity. In order to stop the water spray under these conditions, there is placed in 95 the circulating line a thermostat, indicated generally at 26, controlling a switch 28. This switch is maintained closed below a predetermined temperature of the spray water, but is caused to open by the action of the thermostat when the 100 water temperature rises to a predetermined value. The switch 28 is included in a relay circuit which also includes a relay coil 30 and a battery 32. If desired, a single battery may be used in place of the two batteries 24 and 32. The coil 30 normally maintains closed the stopping relay switch 34 which is connected in a lead between the battery 24 and the pump motor 22. A spring 36 tends to open the switch 34 when the coil 30 is de-energized. Upon an extended stop, therefore, 110

when the refrigerator is inactive, the pump 8 continues to operate until the water temperature rises above the predetermined value for which the thermostat 26 is set, whereupon the 5 switch 34 is opened and the pump is stopped.

With the parts thus far described, it will be noted that upon resumption of operation of the refrigerator, the pump, if already stopped by the 10 opening of the relay switch 34, would have no tendency to start because the thermostatic switch 15 28 will not close until cooled fluid is circulated in the circulating system. In order to provide for the automatic restarting of the circulating system, regardless of the water temperature, a second or starting relay switch 38 is connected in parallel to the switch 34. The switch 38 is adapted to be held open by a spring 40 but is normally held closed when the vehicle is in motion by a relay magnet 42 connected in one of 20 the leads 20 between the axle generator 16 and the refrigerator motor 12. Although the starting switch 38 is open when the car is stationary, it is closed immediately upon restarting of the car. The closure of the switch 38 completes the circuit 25 of the motor 22, thereby starting the pump 8 even though the stopping switch 34 remains open because of the elevated temperature of the water. After a short time, however, the water becomes sufficiently cooled by the action of the refrigerator 30 to effect closing of the switch 34, thereby again placing the system in readiness for operation on the reserve of cooled water at a subsequent stop.

It will be seen that the circulation of water is maintained when either of the relay switches 35 is closed and is shut off only when both switches are open; in other words, circulation is maintained either when the water temperature is sufficiently low or when the refrigerator is active, but is stopped only under the dual condition of high 40 temperature of the water and inactivity of the refrigerator.

Although the preferred form of the invention has been illustrated and described, the invention is not to be considered as limited to the precise 45 construction herein shown, but may be modified within the scope of the appended claims.

Having thus described the invention, what is claimed is:

1. Air conditioning apparatus for vehicles having, in combination, a refrigerator, means for driving the refrigerator, an independently driven liquid circulating system to permit continued operation thereof after cessation of operation of the refrigerator, means for cooling the liquid by 50 the refrigerator, temperature controlled means for shutting off circulation of the liquid when the refrigerator is inoperative and the temperature of the liquid rises to a predetermined value, and means for restarting operation of the liquid circulating system on resumption of operation of the refrigerator.

2. Air conditioning apparatus for vehicles having, in combination, a refrigerator, means for driving the refrigerator from the motion of the 65 vehicle, an independently driven liquid circulating system to permit continued operation thereof after cessation of operation of the refrigerator by stopping of the vehicle, means for cooling the circulating liquid by the refrigerator, temperature controlled means for shutting off circulation 70 of the liquid when the refrigerator is inoperative and the temperature of the liquid rises to a predetermined value, and means for restarting the operation of the liquid circulating system on 75 resumption of operation of the refrigerator.

3. Air conditioning apparatus for vehicles having, in combination, a refrigerator, means for driving the refrigerator, an independently driven liquid circulating system to permit continued operation thereof after cessation of operation of the refrigerator, the fluid circulating system including a dehumidifier and a cooler, a connection between the refrigerator and the cooler, temperature controlled means for shutting off circulation of the liquid when the refrigerator is inoperative and the temperature of the liquid rises to a predetermined value, and means for restarting operation of the liquid circulating system on resumption of operation of the refrigerator.

4. Air conditioning apparatus for vehicles having, in combination, a refrigerator, means for driving the refrigerator from the motion of the vehicle, an independently driven liquid circulating system to permit continued operation thereof after cessation of operation of the refrigerator by stopping of the vehicle, the liquid circulating system including a dehumidifier and a cooler, a connection between the refrigerator and the cooler, temperature controlled means for shutting off circulation of the liquid when the refrigerator is inoperative and the temperature of the liquid rises to a predetermined value, and means for restarting operation of the liquid circulating system on resumption of operation of the refrigerator.

5. Air conditioning apparatus for vehicles having, in combination, a refrigerator, means for driving the refrigerator, an independently driven liquid circulating system to permit continued operation thereof after cessation of operation of the refrigerator, the fluid circulating system including a dehumidifier and a cooler, a connection from the refrigerator to the cooler, and means for stopping circulation of the fluid when the refrigerator is inactive and the temperature of the cooling fluid medium is above a predetermined value.

6. Air conditioning apparatus for vehicles having, in combination, a refrigerator, means for driving the refrigerator, an independently driven liquid circulating system to permit continued operation thereof after cessation of operation of the refrigerator, the liquid circulating system including a dehumidifier and a cooler, a connection from the refrigerator to the cooler, thermostatic means in the circulating system, and means for operating the circulating system either during the operation of the refrigerator or by the presence of liquid at lower than a predetermined temperature in the circulating system.

7. Air conditioning apparatus for vehicles having, in combination, a refrigerator, axle driven means for operating the refrigerator, a cooler cooled by the refrigerator, a dehumidifier, means for circulating a liquid through the cooler, a drive for said circulating means independent of the axle driven means to permit continued circulation of the liquid after stopping of the vehicle, means for stopping circulation of the liquid when the refrigerator is inoperative and upon rise of the temperature of the liquid to a predetermined value, and means for restarting circulation of the liquid upon restarting of the vehicle.

8. Air conditioning apparatus for vehicles having, in combination, a refrigerator having an electric motor, an axle driven generator, electrical connections between the generator and

- the motor, a cooler cooled by the refrigerator, means for circulating a fluid through the cooler, means for conditioning air with the circulated fluid, an electric motor drive for the circulating means, a motor circuit including a source of electrical energy for said electric motor drive independent of said axle driven generator, a thermostatically controlled switch to close the motor circuit upon the circulation of fluid below 5 a predetermined temperature, and a switch operated by the generator to close the motor circuit when the generator is running.
9. Air conditioning apparatus for vehicles having, in combination, a refrigerator having an 15 electric motor, an axle driven generator, electrical connections between the generator and the motor, a cooler cooled by the refrigerator, means for circulating a liquid through the cooler, means for conditioning air with the circulated 20 liquid, an electric motor drive for the circulating means, a motor circuit including a source of electrical energy for said electric motor drive independent of said axle driven generator, two parallel switches in the motor circuit, means 25 for opening one of said switches when the temperature of the circulated liquid rises to a predetermined value, and means for opening the other of said switches upon stopping of the vehicle.
- 30 10. Air conditioning apparatus for vehicles having, in combination, a refrigerator having an electric motor, an axle driven generator, electrical connections between the generator and the motor, a cooler cooled by the refrigerator, 35 means for circulating a liquid through the cooler, means for conditioning air with the circulated liquid, an electric motor drive for the circulating means, a motor circuit including a source of electrical energy for said electric motor drive independent of said axle driven generator, a relay 40 controlled by the temperature of the circulated liquid and having a switch in the motor circuit, and a second relay controlled by the axle driven generator and having a switch in the motor circuit in parallel to said temperature controlled 45 switch.
11. Air conditioning apparatus for vehicles having, in combination, an axle driven refrigerator, a cooler cooled by the refrigerator, a fluid 50 circulating system including the cooler, an electric motor drive for the circulating system, two parallel switches for controlling the electric motor drive, means for opening one of the switches when the temperature of the fluid rises above a predetermined value, and means for 55 opening the other switch upon stopping of the vehicle.
- 60 12. A method of conditioning air for a vehicle having an axle driven refrigerator which consists in continuously circulating a liquid in heat exchange relationship with the air, cooling the liquid by the refrigerator, stopping the circulation of the liquid upon rise of the liquid to a predetermined temperature when the vehicle is stationary, and resuming circulation of the liquid upon restarting of the vehicle.
- 65 13. Air conditioning apparatus having, in combination, a liquid circulatory system, refrigerating means for cooling the liquid in the system, means operating independently of the operation of the refrigerating means for causing circulation of the liquid in the system, and temperature controlled devices for shutting off the circulation
- of the liquid when the refrigerating means are inoperative and the temperature of the liquid rises to a predetermined value.
14. Air conditioning apparatus having, in combination, a liquid circulatory system, refrigerating means for cooling the liquid in the system, means for causing circulation of the liquid in the system, and control devices for throwing said liquid circulatory means out of operation when the liquid rises to a predetermined temperature following a cessation of the operation of the refrigerating means and for throwing said liquid circulatory means into operation upon a resumption of the operation of the refrigerating means. 80
15. Air conditioning apparatus having, in combination, a liquid circulatory system, intermittently operating refrigerating means for cooling the liquid, means for causing circulation of the liquid in the system, and devices for maintaining the liquid circulatory means in operation while the refrigerating means are in operation and for continuing said liquid circulatory means in operation after the refrigerating means have become inoperative and until the liquid rises to a predetermined temperature. 85
16. Air conditioning apparatus having, in combination, a liquid circulatory system, intermittently operating refrigerating means for cooling the liquid, a pump for causing circulation of the liquid in the system, a motor for the pump, and a motor switch thermostatically controlled by the temperature of the liquid in the system for stopping the operation of the pump motor when the liquid rises to a predetermined temperature. 90
17. A method of conditioning air which consists in circulating a liquid in heat exchange relationship with the air, intermittently cooling the liquid, continuing the circulation of the liquid after the cooling has stopped and until the liquid rises to a predetermined temperature, and then stopping the circulation. 95
18. A method of conditioning air which consists in circulating a liquid in heat exchange relationship with the air, intermittently cooling the liquid, continuing the circulation of the liquid after the cooling has stopped and until the liquid rises to a predetermined temperature, then stopping the circulation, and resuming the circulation of the liquid when the cooling is resumed. 100
19. Air conditioning apparatus having, in combination, a cooler in heat exchange relationship with air, means for supplying the cooler with cooling medium, said means including a compressor driven from the motion of the vehicle, and temperature controlled devices for controlling the supply of cooling medium to the cooler operating to continue such supply after the cessation of operation of the compressor by stopping of the vehicle and to cut off such supply when the temperature of the medium rises to a predetermined point. 110
20. A method of conditioning air which consists in circulating a cooling medium in heat exchange relationship with the air, intermittently absorbing heat from the medium, continuing the circulation of the medium after the absorbing of the heat therefrom has stopped and until the medium rises to a predetermined temperature, then stopping the circulation, and resuming the circulation of the medium when the absorbing of the heat therefrom is resumed. 115
